Primary Examiner — Elizabeth J Oswecki(74) *Attorney, Agent, or Firm* — Ryan Dean; Umberg Zipser LLP(57) **CLAIM**

The ornamental design for a secured container, as shown and described.

DESCRIPTION

FIG. 1 is a perspective view of a secured container, showing my new design, with the lid in an open position.

FIG. 2 is a perspective view of FIG. 1, with the lid in a closed position.

FIG. 3 is a front elevation view of FIG. 1.

FIG. 4 is a back elevation view of FIG. 1.

FIG. 5 is a left side elevation view of FIG. 1.

FIG. 6 is a right side elevation view of FIG. 1.

FIG. 7 is a top plan view of FIG. 1; and,

FIG. 8 is a bottom plan view of FIG. 1.

The broken lines shown in the drawings represent portions of the secured container that form no part of the claimed design.
